UNITED STATES PATENT OFFICE

JOHN G. SHODRON, OF FORT ATKINSON, WISCONSIN, ASSIGNOR TO JAMES MANUFACTURING COMPANY, OF FORT ATKINSON, WISCONSIN, A CORPORATION OF WISCONSIN

PUTTY SHIELD

Original application filed March 6, 1929, Serial No. 344,640. Divided and this application filed April 21, 1930. Serial No. 445,939.

My invention relates to improvements in putty retainers, this application being filed in response to a requirement for division made in my earlier application, Serial No. 344,640, filed March 6, 1929, for metal weather shields for doors and windows. In the present application I have shown and described my invention as applied to metal frames of the type shown in my former application, but I also illustrate two modifications adapted for use in connection with frames formed of wood. This is, therefore, a companion application which includes subject matter divided from said former application.

Objects of this invention are to provide means for anchoring putty covering shields to the frame member in such a manner that the shield may be held or anchored along opposing margins by anchoring members which do not materially interfere with the adhesion of the putty to the frame and to the glass or panel, to be attached to the frame in a weather-tight joint.

A general object of my invention is to provide means for utilizing the adhesive quality of the putty to make the weather-tight joint while covering and protecting the putty from disintegration, either by reason of exposure to weather or to the attacks of birds or animals.

A further object is to provide simple, inexpensive and effective means, cooperative with the putty, for making durable weather-tight joints for window glass and panels.

In the drawings:

Figure 1 is a fragmentary elevation of a poultry house sash and door assembly to which my invention has been applied.

Figures 2, 3 and 4 are sectional views, taken on lines 2-2, 3-3, and 4-4, respectively, of Figure 1.

Figure 5 is a fragmentary isometric view of one of the intermediate or cross rails of the sash, showing three anchor strips as they appear at different stages of the glazier's operation and a fourth anchor strip in its final or shield retaining position.

Figures 6, 7 and 8 are fragmentary views of wooden sash, showing modifications.

Like parts are identified by the same reference characters throughout the several views.

The sash frame 10 is provided with cross rails 11 and 12 which subdivide the frame and cooperate therewith in supporting the panes of glass 13. The rail 12 serves also to support a door 14 connected to that rail by hinges 15.

In the construction shown, the frame 10 is formed of metal having a web 18 along the inner margin of the frame bar, said web having a shoulder flange 19 along its otherwise free margin which serves as a ledge 19 to support associated panes of glass 13. The intermediate or cross rails 11 have similar ledges 20 (Figure 5). Each of these ledges 19 and 20 has an obliquely upturned edge margin 21 which forms with the ledge and the web 18 or with the wall of the intermediate rail 11, a putty receiving space 22, this space being filled with putty before the associated pane of glass 13 is applied to the ledges. The cross rails 11 have double webs 18, each with a web 20, since they receive and support glass at both sides.

As shown in Figure 5, the intermediate rails are each preferably formed by folding a strip of sheet metal along its medial line and turning its marginal portions outwardly in opposite directions to form the ledges 20 and then upwardly in an oblique plane to form the putty retaining members 21 for the putty receiving cavity 22.

Each of the webs 18 is provided with sets or pairs of slots 25 and 26 at suitable intervals along their length. The slots 25 are preferably located substantially in the plane of the glass pane 13 (or a little below that plane) and the pane receiving frame openings are made slightly larger than the pane of glass, whereby putty anchoring and shield retaining strips of sheet metal may be passed through these slots from the opposite side of the web or of the frame member 11 and turned upwardly until after the glass has been placed in position, whereupon the end of each strip which passes through the slot 25 may be bent downwardly along the surface of the glass pending application of another body of putty to its exterior surface.

Preferably each of these anchor strips is of staple form, with a middle portion 28 connecting elongated arms 29 and 30 of unequal length, the arm 29 being preferably longer than the arm 30, whereby it may be upturned across the edge of the glass, as indicated at 31 in Figure 5, and then bent downwardly upon the surface of the glass in the portion 32.

10 After the glass has been placed in position, and the arms 32 of the anchor strip folded over upon its outer surfaces, the glass retaining band or body 35 of putty is then applied in the usual manner to secure the 15 glass to the frame, this band or body of putty being preferably triangular in cross section in accordance with the usual practice.

Thereupon a strip of metal, in the form of a shield 37, having a width corresponding 20 substantially with that of the oblique surface of the putty band, will be applied thereto and secured by folding the extremities 38 and 39 of the anchor strips over the edge margins of the shield 37. This shield is 25 preferably slightly ribbed or corrugated, as indicated at 40 in Figure 5, whereby the same is sufficiently reinforced to allow very thin material to be employed without danger of displacement.

30 My invention is particularly applicable to metal sash frames, formed of sheet metal or other material which can be readily slotted to receive the anchor strips without materially weakening the structure. It is also applicable to wooden sash frames in a slightly 35 modified form as shown in Figures 6 and 7. By this modified form of construction, staples are employed to secure the anchor strips in position, and in Figure 6 I have illustrated 40 a sheet metal staple 42 which engages the middle portion 28a of a sheet metal anchor strip, the staple being so located that the longer arm, 29a, may be upturned across the edge of the glass as indicated at 31a, thereby 45 making it possible to use the anchor strips in the same way, or to use anchor strips exactly like those shown in Figure 5.

In Figure 7 a wire staple 43 is used in connection with wire anchor strips, otherwise 50 similar to those shown in Figure 6. The Figure 8 modification preferably employs flat metal anchor strips 43 and 44, each having its inner end elbowed and tapered to provide a tack-like point which may be 55 driven into the wood to connect the associated anchor piece thereto. In this construction the two arms of the anchor are separately connected with the wood.

In Figure 6 parts corresponding with those 60 shown in Figures 1 to 5, bear the same reference characters with letter "a" added. In Figure 7 the letter "b" is added.

It is, of course, not material to the invention herein claimed whether the putty is employed to anchor a pane of glass in position 65

or to form an air-tight closure for any other type of joint having a support to which putty may adhere.

From the foregoing description it will be understood that my invention permits a glass 70 pane or other plate-like member to be secured in a frame opening by a body of putty in adhesive relation to the frame and the plate-like member or pane of glass substantially in accordance with common practice as heretofore followed, but with the additional protection afforded by the shield, and the additional security in the fastening of the shield, due to the fact that it is connected with the frame along opposite margins. It is thus 75 80 possible to utilize, to the fullest possible extent, the adhesive characteristic of the putty, whereby air and water are excluded from the joint.

Also, the anchoring strips are themselves 85 anchored by the edge of the glass as well as by their inter-lock with the frame, and in the structure shown in Figures 1 to 5, inclusive, the body of putty extends entirely around the edge margins of the glass and is, 90 in part, covered by the ledge 19 (or 20). Ordinarily the body of putty on the ledge will remain soft until the pane of glass has been placed in position and the putty applied to the opposite side, in which event, the two 95 bodies of putty will merge and form a homogeneous mass.

I claim:

1. The combination with a support, of a member in jointed connection therewith, a 100 body of putty covering the joint, and a thin strip of metal covering the putty and separately anchored to the support at intervals along each side margin, said body of putty being in adhesive engagement with the support and said member between said points of anchorage.

2. The combination with a support having pairs of slots at intervals along its length and provided with a shoulder having a putty 110 retaining channel, a plate-like member engaging said shoulder substantially in the plane of one slot of each pair, with putty interposed between it and said shoulder, a body of putty connecting the support and 115 plate-like member on the side opposite that occupied by the shoulder, a shield covering said body of putty, and anchor strips extending through said slots and along two sides of the body of putty, and having extremities 120 engaging opposing margins of the shield at intervals along its length.

3. In a window sash, the combination with a sash rail and a pane of glass puttied at the joint formed by the glass and rail, of a shield 125 of non-frangible material covering the putty, and anchor strips located at intervals along said joint, each with a middle portion engaged with the rail, and arms, one of which extends upwardly along the surface of the rail with 130

an extremity engaging the shield along one margin and the other of which extends inwardly along the pane of glass with an extremity engaging the opposing margin of

5 the shield.

4. In a window sash, the combination with a sash rail and pane of glass puttied at the joint, of a shield of non-frangible material covering the putty, and anchor strips engaged with said rail at intervals, with one arm extending upwardly along the surface of the rail and engaging the shield along one margin and another arm extending inwardly along the pane of glass and engaged 10 with the opposing margin of the shield, each anchor strip also having one portion interposed between the edge of the pane of glass and the sash rail.

5. A puttied joint provided with a thin 20 metal covering shield in combination with spaced anchoring strips, each secured to one of the jointed members and having arms extending divergently underneath the putty and embracing opposing margins of the 25 shield, said joint comprising connected members in adhesive relation to the putty between the anchoring strips.

6. A metal sash rail having a pane supporting flange and a web provided with 30 pairs of slots at intervals, disposed with one slot of each pair in proximity to said flange, a pane of glass supported from said flange and having its edge margin embedded in a body of putty adhesively securing both sides 35 thereof to the flange and the web, staple-like anchor strips having arms extending through said slots, with one arm bent upwardly along the web and the other arm extending along the surface of the glass, and a 40 metal shield covering the putty, with its margins engaged by the extremities of said anchor strips.

7. The combination with a window sash frame and a pane of glass having its margins embedded in joint closing material in adhesive relation to the glass and to the sash frame, of a nonfrangible covering, co-operative with the sash frame to substantially wholly enclose the adhesive material, and 45 anchor members having medial portions interlocked with the frame and provided with arms, one extending transversely along one surface of the frame members with which it is associated, and the other extending in a 50 plane perpendicular to said frame member, the extremities of the arms being hooked over opposing margins of said covering.

JOHN G. SHODRON.
